(57) **CLAIM**

We claim the ornamental design for a loudspeaker accessory tray, as shown and described.

DESCRIPTION

FIG. 1 is a front, top, right perspective view of a loudspeaker accessory tray according to the present invention;

FIG. 2 is a rear, top, right perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof;

FIG. 8 is a bottom view thereof; and,

FIG. 9 is a front, top, right perspective view thereof as mounted to the top of a loudspeaker.

The dashed lines illustrate portions of the loudspeaker accessory tray, and also environment in FIG. 9, that form no part of the claimed design. The dash-dot-dash lines of FIGS. 1, 2, 7, and 9 illustrate a boundary of the claimed design and form no part of the claimed design.
